UNITED STATES PATENT OFFICE.

FREDERICK G. SARGENT, OF WESTFORD, MASSACHUSETTS.

METHOD OF AND APPARATUS FOR SELECTIVE WIRELESS TELEGRAPHY.

1,091,768.

Specification of Letters' Patent. Patented Mar. 31, 1914.

Application filed November 14, 1912. Serial No. 731,272.

To all whom it may concern:

Be it known that I, FREDERICK G. SARGENT, a citizen of the United States, residing at Westford, in the county of Middlesex and State of Massachusetts, have invented a new and useful Method of and Apparatus for Selective Wireless Telegraphy, of which the following is a specification.

This invention relates to a system of communicating or telegraphing, and for other purposes particularly adapted for use with wireless apparatus.

The principal objects of the invention are to secure secrecy and simplify both the sending and receiving operations.

The invention also involves improvements in features of construction and combinations of parts as will appear hereinafter.

Reference is to be had to the accompanying drawings in which—

Figure 1 is a diagrammatic elevation of a sending station; Fig. 2 is a similar view of a receiving station adapted to coöperate therewith; Fig. 3 is a view of one of the 25 dials showing a modification, and Fig. 4 is a similar view showing another modification.

Referring to Figs. 1 and 2 it will be seen that at each station there are two members one rotary and one stationary; namely a 30 dial 10 and a pointer or indicator 11. For the purpose of this invention either the dial or the pointer may rotate and in the form shown in Figs. 1 and 2 the dial is intended to be stationary and the indicator to rotate. 35 The means for rotating the rotatable member is not shown herein but any well known form of clock work or other rotating mechanism can be employed. It is intended to have the rotation at the several stations synchronous. For this purpose the instruments 40 can be set or adjusted by the time signals sent out by the wireless stations every day or they can be provided with extremely accurate instruments so they will keep correct 45 time with each other. At any rate, when commencing to operate, the stations can be adjusted to see if they are in unison by any simple means.

With the parts arranged as so far described, the apparatus can be used with any ordinary sending and receiving system, either wireless or otherwise. This mode of operation is as follows: The station wishing 50 to talk calls the other station or stations in any usual way. After receiving the answer they can, if necessary, compare their dials 55 to see that they are in unison and if not, adjust them so that they will be. The several dials, being provided with series of characters arranged in the same order thereon 60 and rotating in the same direction, or the indicator rotating in the same direction as the case may be, the operators at the stations can give a pre-arranged signal, as for example "a" and if the signal is received 65 at the stations when the indicators and dials are at that point it will be understood that all the instruments are in unison. The sending operator then sends signals by giving any predetermined signal, as a dash or dot, 70 over the apparatus when the indicator 75 indicates the desired letter or character on his dial. The instruments being in unison and the signal being sent instantaneously the receiving station will get the signal when its indicator is showing the same letter or character. It will be understood of course that ordinarily the same signal will be sent over the wireless apparatus each time so that to any station not having this apparatus the communications from the sending station would appear to be a repetition of 80 the same signal but at unequal intervals. This system can be used also in actual connection with the wireless apparatus now in 85 use and for this purpose the following connections are shown. On each of the dials 10 there are a series of contacting pins 12 corresponding in number with the characters on the dials, and the indicator 11 contacts with 90 these periodically as it rotates. In Figs. 1 and 2 the indicator is shown as having a projection 13 for this purpose and the pin with which this projection is shown in contact in Fig. 1 would represent the character 95 A or 1. From each of these pins 12 a conductor 14 is taken off which is connected with a push button 15 having a character thereon corresponding with the character which the indicator shows when that pin 12 100 is in contact with it. These push buttons 15 thus constitute a key board. Each one is provided with a contact 16 which engages a bar 17 when the key is depressed. This bar is connected with an electro-magnet 18 connected with a battery 19. This in turn is connected with the metallic case 20 in which the dial is located, which is electrically connected with the shaft 21 with which the metallic indicator 11 rotates. Consequently as 110 the indicator rotates it periodically closes each of the several circuits one at a time, no

two ever being closed at the same time. The pressing down of any one of the keys 15 of the key board closes that circuit at one point and then the circuit is completed whenever 5 the indicator gets around to the position which indicates the same character. Then the magnet 18 is energized, a contact 22 is made, and a current is set up in the usual primary 23 and secondary 24. The circuit 10 in which the secondary circuit 24 is located is provided with the usual condenser 25, oscillators 26, and aerial 27.

The receiving station is shown of a well known type having the aerial 28, coil 29, 15 condenser 30 and detector 31. It is also provided with a telephone receiver 32 and this circuit is connected up with the dial at this station in a manner similar to that described at the other station, but there is no 20 key board. One end of the circuit is connected with the case of the dial so that it is constantly connected with the indicator and the other end of the circuit is divided into as many lines as there are characters 25 and one connected with each of the pins 12.

It will be understood of course that while I have described a complete sending station and a complete receiving station separate from each other, ordinarily each station 30 will actually be provided with both the receiving and the sending mechanism. In this case the sending station is connected up for receiving purposes by simply switching out the battery 19 and connecting these 35 wires to a telephone circuit located as at what I have called the sending station. In either case the telephone circuit is closed only when the dial and indicator are in the same relative position as that in which 40 they are in at the sending station. At other times nothing can be heard on the telephone receiver as its connections are broken. It will be understood, of course, also that the telephone receiver can be dispensed with 45 and a coherer used in the ordinary way for operating the relay. The relay then can operate lights or other apparatus for signals or other desired kind of communication or purposes. It will be understood, of course, 50 also that the clock mechanism for operating the dials or indicator can be made to run only for a definite period of time if desired before requiring rewinding, or that the same can be made on the same principle as a stop 55 watch so that it can be stopped and started as desired to save some of the rewinding. With a stop watch arrangement it can be arranged to start always on a definite character and then the device can be employed 60 to place the several stations in unison. It will be understood of course that the clock work can be regulated so that the hand or dial can be made to revolve at any convenient speed, depending upon the size thereof 65 and the distance apart of the characters.

In Fig. 3 another construction is shown in which the dial 35 rotates and is provided with a cover 36 having openings 37 therethrough constituting an indicator so that it will be simpler for the operator to tell 70 which character is in the position for communication. The keys and contacts are used as in Fig. 1. In Fig. 4 another similar construction is shown in which there is a relative rotation between the dial 38 and the 75 cover 39, a space 40 being provided for the purpose of designating the position of the letter called. This is merely an indicator without electrical connections. Whether connected up as described or used simply as 80 a selective signaling device without the electrical connections, it is obvious that such an arrangement will prevent the reading of the messages by any party not having such a device and yet the operations of receiving 85 and sending are simpler than they are with the types of wireless apparatus now in use.

Although I have illustrated and described only a few modifications of the invention, I am aware of the fact that other changes 90 can be made therein by any person skilled in the art without departing from the scope of the invention as expressed in the claims. Therefore, I do not wish to be limited to all the details herein shown and described, but 95

What I do claim is:—

1. The improvement in the art of sending messages, which consists in synchronously and continuously, but independently, revolving indicators relatively to similar dials 100 having characters thereon arranged in the same way at the sending and receiving stations respectively, sending a signal from the sending to the receiving station at the instant that the indicator shows a desired 105 character on the dial at the sending station, whereby the operator at the receiving station will determine the character intended to be sent by noting what character on his dial is indicated by his indicator when he receives 110 the signal.

2. The improvement in the art of wireless telegraphy which consists in synchronously and continuously revolving pointers relatively to similar dials having characters 115 thereon arranged in the same way at the sending and receiving stations respectively, sending a signal by wireless means from the sending to the receiving station at the instant that the indicator shows a desired 120 character on the dial at the sending station, whereby the operator at the receiving station will determine the character intended to be sent by noting what character on his dial is indicated by his indicator when he 125 receives the signal.

3. In a wireless telegraph apparatus, the combination of a set of dials and indicators therefor, one at each station, means for rotating said dials and indicators at each sta. 130

tion relatively to each other, synchronously and continuously, each dial being provided with a series of characters arranged thereon in the same order, a series of contacts corresponding one with each character, circuits connected with said contacts, means for closing each circuit when the indicator of that dial indicates the character corresponding to the contact connected with that circuit, 10 and wireless-telegraph apparatus connected with said circuits.

4. In a wireless telegraph or signaling apparatus the combination of a set of dials and indicators, one at each station, means for 15 relatively rotating the dial and indicator of each station synchronously with the rotation of those of the other station or stations, each dial being provided with a series of characters arranged thereon in the same order at 20 the several stations and with a series of contacts corresponding with said characters, means for engaging said contacts in the same order at the several stations as the rotation is carried on, circuits connected with said contacts, a key-board at the sending station having keys, one connected with each of said circuits, each key corresponding with one of the characters on the dial, a wireless sending apparatus, and means whereby when any 25 key is lowered a circuit to the sending apparatus will be completed with the exception of the making of the contact at the dial.

5. In a wireless telegraph or signaling apparatus, the combination of a set of dials 30 and indicators, one at each station, means for relatively rotating the dial and indicator of each station synchronously with the rotation of those at the other station or stations, each dial being provided with a series of 35 characters arranged thereon in the same order at the several stations and with a series of contacts corresponding with said charac-

ters, means for engaging said contacts in the same order at the several stations as the rotation is carried on, circuits connected with 45 said contacts, a key-board at the sending station having keys, one connected with each of said circuits, each key corresponding with one of the characters on the dial, a wireless sending apparatus, means whereby when 50 any key is lowered a circuit to the sending apparatus will be completed with the exception of the making of the contact at the dial,

55 a corresponding number of partial circuits at the receiving station each adapted to be closed by the relative rotation of the dial and indicator in the same order as at the sending station, and means in series with all of said partial circuits at the receiving station for detecting the sending of a signal. 60

6. In a wireless telegraph or signaling apparatus, the combination of a set of dials and indicators, one at each station, means for relatively rotating the dial and indicator of each station synchronously with the 65 rotation of those of the other station or stations, each dial being provided with a series of characters arranged thereon in the same order at the several stations and with a series of contacts corresponding with said 70 characters, means for engaging said contacts in the same order at the several stations as the rotation is carried on, circuits connected with said contacts, and a key-board at the sending station having keys, one connected 75 with each of said circuits.

In testimony whereof I have hereunto set my hand, in the presence of two subscribing witnesses.
